Inventor,
KENNETH I. SMALL
By Marcus A. Hirsch
Atty.

UNITED STATES PATENT OFFICE.

KENNETH I. SMALL, OF NEW YORK, N. Y., ASSIGNOR TO GEORGE T. HORTON, OF CHICAGO, ILLINOIS.

TANK.

1,343,412.

Specification of Letters Patent. Patented June 15, 1920.

Application filed June 23, 1919. Serial No. 306,227.

To all whom it may concern:

Be it known that I, KENNETH I. SMALL, a citizen of the United States, residing at New York, in the county of Queens and State of New York, have invented new and useful Improvements in Tanks, of which the following is a specification.

This invention relates to improvements in water tanks of the general type disclosed in patents to George T. Horton, No. 857626 issued June 25, 1907; No. 1008645 issued November 14, 1911; No. 1177704 issued April 4, 1916 and No. 1184347 issued May 23, 1916. Such a tank comprises in general the tank structure proper with an inclined bottom and supporting legs, and is additionally supported by a central water leg or cylinder which joins the bottom of the tank and forms a settling basin for mud and sediment. An inlet pipe is ordinarily arranged to supply water up through the settling basin or water leg.

It has been found that when the tank is used in cold climates some protection is needed to prevent freezing of the water. In Patents Nos. 1177704 and 1184347 there is shown a tank with the water leg or cylinder divided by a false bottom into an upper and lower compartment; the former communicating with the tank above and filled with water, and the latter affording a heating chamber in which is placed a stove or other suitable heating device. In the center of the false bottom is cut a circular opening into which is inserted the stove pipe of the stove, and the smoke and products of combustion are conducted upward through the entire height of the tank and through the roof by means of an iron or steel pipe, the bottom end of which is connected with the circular opening in the center of the false bottom. It has been found in practice, that in some cases such means for warming the water are objectionable owing to the fact that the water in contact with the pipe passing through the tank cools it to such an extent as to impair the draft of the stove below, and causes condensation of moisture in the air in the pipe to such an extent as to interfere with combustion.

Accordingly the present invention relates more particularly to means for warming

the water in the tank to prevent freezing which means are not subject to the objections noted above.

A device embodying the principles of the present invention is illustrated in the accompanying drawings in which:

Figure 1 is a view of the tank in vertical axial section.

Fig. 2 is an enlarged view in vertical section showing the means for collecting and disposing of the condensation of water.

As shown in said drawings that part of the inclined bottom of the tank (of the general construction described in said prior patents) which joins the central water leg is indicated at 10, and the water leg or cylinder is indicated at 11. The cylinder 11 is divided by a false bottom 15 into an upper and lower compartment; the former communicating with the tank above and filled with water, and the latter affording a heating chamber in which is placed a stove or other suitable heating device 16, while access is afforded thereto through a door, not shown. A water supply pipe 24, extends up through the lower compartment of the cylinder 11, passes through the curved bottom 15 and extends to a sufficient height into the water chamber above to prevent the inflowing currents of water from disturbing the sediment in the cylinder. The top of the tank is covered by a conical roof 8, which may be of any ordinary form of construction, supported by the brackets 91, 91 a sufficient height above the edge of the tank in order to leave openings between the top edge of the tank and the eaves. To a circular opening in the center of the bottom 15 is joined a large steel heating drum 90 which extends upward through the water in the tank and terminates above the highest level of the water and below the roof 8. 30 indicates a chimney or flue for the stove 16 which extends upwardly from the stove through the heating drum 90, through the entire height of the tank, and through an opening 9 in the roof 8. The diameter of the flue or chimney 30 is substantially smaller than the diameter of the steel heating drum 90 in order to afford an air space between the two and permit warm air to pass through the heating drum 90 outside of the

flue 30 and discharge into the space above the water and below the roof, from which space it may escape into the outer atmosphere by going through the spaces under 5 the eaves of the roof.

It is evident that in some cases, the cooling effect of the water on the steel drum 90 will cause condensation of moisture on its inner wall, and that this moisture may accumulate to such an extent as to flow downward and out of the bottom of the drum 90. I have provided means as follows for collecting and disposing of such moisture. A short distance below the lower end of the 15 drum 90 and supported from the bottom by the brackets 93, is a circular trough 94, the center of said trough being directly below the inner edge of the lower end of the drum 90. A pipe 95 leading from a hole 20 in the bottom of the trough is provided for the purpose of draining the same and discharging the contents outside of the structure at 96.

In order to conserve heat, the cylinder 11 25 is surrounded by a shell or frost casing 34 which may be made of steel, tile, brick, wood, or other suitable material, and is spaced away from the cylinder wall in order to form an air space between such wall and 30 the casing. Openings 7, 7 are provided in the cylinder 11 below the false bottom 15 to permit the circulation of air in order that warm air from the heating chamber may enter the space between the cylinder 11 and 35 the shell or frost casing 34.

A pipe, not shown, passing through the frost casing 34 and the cylinder 11 below the false bottom 15 is arranged for admitting fresh air to the heating chamber from the 40 outside.

I claim:

1. In a water tank, a heating chamber with a heat conducting drum extending from said chamber through the water in the 45 tank, and a heating device in said heating

chamber with a chimney or flue extending through said heat conducting drum.

2. In a water tank, a heating chamber with a heat conducting drum extending from said chamber through the water in 50 the tank, and a heating device in said heating chamber with a chimney or flue substantially smaller than the drum extending through said drum.

3. In a water tank, a heating chamber 55 with a heat conducting drum extending from said chamber through the water in the tank, a heating device in said heating chamber with a chimney or flue extending through said drum, and means below said 60 drum for collecting condensation of moisture in said drum.

4. The combination with an elevated water tank having its bottom joined to a central member of less diameter than the 65 diameter of the tank, such central member connecting with the interior of said tank and adapted to contain water, of a false bottom in said member, a heating device below such false bottom, a heat conducting 70 drum joining said false bottom and extending upward through the water in the tank, and a flue or chimney extending from the heating device through the drum.

5. The combination with an elevated 75 water tank, having its bottom joined to a central member of less diameter than the diameter of the tank, such central member connecting with the interior of said tank and adapted to contain water, of a false bot- 80 tom in said member, a heat conducting drum joining said false bottom and extending upward through the water in the tank, and a chimney or flue passing through the 85 drum.

In witness whereof, I have hereunto subscribed my name this 16th day of June, 1919.

KENNETH I. SMALL.
